UNITED STATES PATENT OFFICE.

BENJAMIN HALL, OF NEVADA CITY, CALIFORNIA.
TURBINE.

Application filed March 16, 1921. Serial No. 452,650.

To all whom it may concern:

Be it known that I, BENJAMIN HALL, a citizen of the United States, residing at Nevada City, in the county of Nevada and State of California, have invented new and useful Improvements in Turbines, of which the following is a specification.

This invention relates to a turbine.

It is the principal object of the present invention to provide a turbine structure which may be used with a fluid to produce motion, or to be used in compressing the fluid.

The present invention contemplates the use of a volute case, within which a laminated rotor is provided, said laminations being spaced from each other to afford surface friction to the fluid passing through the case.

20 The invention is illustrated by way of example in the accompanying drawings, in which:

Figure 1 is a view in central longitudinal section through the structure.

25 Fig. 2 is a view in central transverse section through the turbine disclosing the relation of the volute case to the rotor.

Referring more particularly to the drawings, 10 indicates a volute case. This structure is substantially circular, having an induction nozzle 11, and eduction passageways 12 and 13. By referring to Fig. 1 it will be noted that the volute case is formed with conical side walls 14 and 15, the conical bases of which structure are coincident along the transverse center of the case. The eduction passageways 12 and 13 communicate with the center of the conoidal case through circular exhaust ports 16. The circumferential portion of the conoidal volute

case is formed with a volute passageway 17 which is a continuation of the tangentially arranged induction nozzle 11 and which passageway decreases in sectional area as it proceeds around the circumference of the case.

A rotor 18 is mounted within the case with its central transverse axis in the same plane with the transverse center of the conoidal case. The rotor is mounted upon a shaft 19 disposed eccentrically of the volute

case and extending thereacross. Suitable stuffing boxes 20 are secured at the opposite sides of the case and receive the rotor shaft 19. The rotor itself is formed with a plurality of laminated disks. In the case of 55 large turbines the central disk 21 may be of greater section than the remaining disks at either side thereof. The central disk 21 is formed with a knife edge circumference which is beveled from both faces of the disk, 60 and which edge terminates in the center of a throat 22, establishing communication between the conoidal central chamber of the rotor and the volute passageway 17. This will divide the throat and deflect the fluid 65 passing therethrough into two equal volumes, which will thereafter encounter the surfaces of other rotor disks.

In the present instance three other sets of disks are shown as indicated at 23, 24 and 70 25. These disks are all formed with double knife edges and are arranged and designed to insure that a uniform distribution of the motive fluid will be made throughout the rotor and that the necessary expansion of 75 the fluid may take place as its force is expended and as the fluid travels toward eduction openings 25' in each of the disks. These openings as shown in Fig. 1 are of gradually increasing area toward the outside of the 80 rotors and are arranged to permit a flow of the fluid directly through the exhaust ports 16 and into the eduction passageways 12 and 13. Spacing washers 27 are disposed between the various plates and form the hub 85 of the rotor. These washers and the plates are secured together by fasteners such as rivets 28 and are fixed to the rotor shaft 19. In the form of the invention shown in Fig. 1 the various rotor laminations are convexed 90 so that the fluid travelling toward the center will be given an impetus as it is expelled through the openings 26. In some forms of the device this structure might be slightly modified to provide substantially conical 95 rotor plates without sacrificing any of the advantages obtained by the device.

In operation of the present invention the turbine may be either used as a power generator or as a pump or compressor. When 100

used as a generator a fluid is delivered to the nozzle 11 under high pressure and velocity. This nozzle is tangent to the circumference of the volute case and will direct the fluid into the volute passageway 17 which gradually decreases in its sectional area. This arrangement will cause the gases to pass through the annular throat 22 leading from the passageway 17 to the main chamber of the case, at the same time a spiral motion will be imparted to the fluid as it is divided into various streams which pass between the laminations of the rotor. It is intended that the laminations shall be so arranged as to equally divide the volumes of fluid passing therebetween but if this does not exactly occur, equilibrium may be established by the passage of fluid through slots 29 in the disks. These slots are formed with substantially radial knife edges which will offer slight resistance to the fluid as it passes through the disk. As shown in the drawings, sets of these slots are arranged in alignment along different circles on the disks. The passage of the fluid between the plates will cause a rotation of the rotor in the direction of travel of the fluid which rotation will be imparted to the shaft 19. The fluid may then pass from the case through the eduction passageways 12 and 13. If the turbine is to be used as a pump or a compressor the rotor 19 is driven at a high rate of speed, and will act to impart motion to a fluid drawn in the case, which fluid will be expelled through the tangential nozzle 11.

It will thus be seen that the turbine here disclosed, while of simple construction, yet provides effective means for obtaining power from a motive fluid or for imparting motion to a fluid.

While I have shown the preferred form of my invention as now known to me, it will be understood that various changes might be made in the combination, construction and arrangement of parts by those skilled in the art, without departing from the spirit of the invention, as claimed.

Having thus described my invention, what I claim and desire to secure by Letters Patent is:

1. A turbine comprising a volute casing having induction and eduction ports, and a rotor composed of two connected sets of spaced conoidal vanes, the vanes of each set varying in diameter and the bases of the sets coinciding.

2. A turbine comprising a volute casing having a tangentially disposed induction port and central eduction ports, a circular passageway extending around and within the casing, one end of which is in communication with said induction port and the section of which circular passageway gradually decreases, and a rotor within the casing, said rotor being composed of two sets

of spaced conoidal vanes and the bases of the two sets coinciding.

3. A turbine comprising a volute case having a central chamber formed by two convexed side members, the bases of which coincide, a circular passageway extending around said chamber and in communication therewith throughout its length, said passageway gradually decreasing in sectional area, a tangentially arranged nozzle formed as a continuation of the large end of said circular passageway, central eduction ports at the center of said chamber and through which a fluid may pass from the circular passageway to the eduction ports.

4. A turbine comprising a volute case having a central chamber formed by two convexed side members, the bases of which coincide, a circular passageway extending around said chamber and in communication therewith throughout its length, said passageway gradually decreasing in sectional area, a tangentially arranged nozzle formed as a continuation of the large end of said circular passageway, central eduction ports at the center of said chamber and through which a fluid may pass from the circular passageway to the eduction ports, and means for dividing the motive fluid so that substantially equal volumes will pass between the various plates of the rotor.

5. A turbine comprising a volute case having a central chamber formed by two convexed side members, the bases of which coincide, a circular passageway extending around said chamber and in communication therewith throughout its length, said passageway gradually decreasing in sectional area, a tangentially arranged nozzle formed as a continuation of the large end of said circular passageway, central eduction ports at the center of said chamber and through which a fluid may pass from the circular passageway to the eduction ports, means for dividing the motive fluid so that substantially equal volumes will pass between the various plates of the rotor, and means for permitting a gradual expansion of the motive fluid as it passes through and around the rotor.

6. A turbine comprising a volute case having a central chamber formed by two convexed side members, the bases of which coincide, a circular passageway extending around said chamber and in communication therewith throughout its length, said passageway gradually decreasing in sectional area, a tangentially arranged nozzle formed as a continuation of the large end of said circular passageway, central eduction ports at the center of said chamber and through which a fluid may pass from the circular passageway to the eduction ports, means for dividing the motive fluid so that substantially equal volumes will pass between the

various plates of the rotor, means for permitting a gradual expansion of the motive fluid as it passes through and around the rotor, and means for permitting an equilibrium of pressure of the motive fluid between the various plates of the rotor.

7. A turbine comprising an outer case,

into which a fluid under pressure is delivered, and a rotor comprising a plurality of spaced disks varying in diameter to agree with the contour of the casing and between which disks the fluid passes.

BENJAMIN HALL.
